UNITED STATES PATENT OFFICE.

ANGEL A. GRASSI AND RAFAEL DE OLIVEIRA CÉZAR, OF BUENOS AIRES, ARGENTINA.

AUTOMATIC CONTROLLING DEVICE FOR ELECTRIC WATER HEATERS.

Original application filed August 30, 1926, Serial No. 132,498. Divided and this application filed February 18, 1928. Serial No. 255,366.

Our present invention relates to an automatic electric water heater, its main object being to provide an electric water heater for any suitable use, which includes an automatic device for controlling the electric circuit. This application is a division of my co-pending application, Serial No. 132,498, filed August 30, 1926, and this application relates to the automatic device.

10 In order that our invention may be clearly understood and easily carried into practice, a preferred embodiment thereof has been shown in the appended drawings wherein,

15 Figure 1 is a vertical section of the apparatus showing the main elements thereof.

Fig. 2 is a plan view of the heater, and

Fig. 3 is a side elevation thereof.

Similar characters of reference denote the same or like parts throughout the said drawings.

The apparatus has been shown without its outer envelope or casing, and it is obvious that changes in size may be introduced without departing from the scope of the invention.

25 The apparatus includes several elements. The heating tube proper consists of a glass tube T through which water circulates and within which a resistance B is placed, said resistance consisting of several wound up

30 wires and being fixed at its ends to the metal tube C. This tube C consists of two electrically insulated portions. The glass tube fits within the metal tube with an intermediate rubber or insulating tube G fixed under pressure.

35 S is the outlet for the hot water and S' the inlet, they being respectively at the upper part and at the lower part of the heating tube.

Under the term "automatic" we desire to 40 indicate the device by which the electric circuit and the water flow are automatically regulated. H is the body portion of the automatic device having an inner cylindrical section in which a piston D having a contact

45 member Z thereon is capable of reciprocating. Said piston has a rod E secured thereto and is held in its upper position by the action of the springs R. The rod E passes through a stuffing-box K in order to avoid the escape of

50 water which enters the body of the automatic device through the tube F. N is a metal cross piece mounted upon the rod E and supporting at its ends the insulating pieces P on which the upper contact members O are fixed,

55 said contacts being the terminals for the

wires A, through which current is fed to the apparatus.

On the body of the automatic device there is a metal piece U on which two insulating members Q are fixed, said members carrying the contacts S' placed below and separated from the contacts O. One of the said contacts is connected by a wire V' to the copper portion of the tube C while the other contact S' is connected by means of another wire V to a contact member I placed within the device at the bottom thereof and electrically insulated therefrom by the pieces J and L.

The tube F is connected to a water pipe while the outlet S is connected to one or more 70 cocks.

When the cocks are closed the parts will be in the positions shown in the drawings, the heater and the automatic device will be full of water and the electric circuit will be cut 75 off.

When a tap or cock is opened, the water, due to the pressure set up by the circulation enters the automatic device and presses down the piston D against the action of the springs 80 R and keeps it down so long as the water flows, that is so long as any of the cocks are open.

In these circumstances, the upper contacts O will contact with the contacts S', one of which leads to the upper end of the resistance B while the other is connected to the contact I, against which the contact Z of the piston closes, thereby closing also the electric circuit to the lower end of the said resistance B. At the same time the water flows through the device and circulates up to the heating tube 90 through S', and issuing as hot water through the upper end of the said tube.

When the tap is closed, the water remains 95 stationary within the apparatus and automatic device, and the piston D is raised by the springs R, thereby cutting off the current first between the contacts Z and I and then at the contacts O and S'. No sparking will 100 take place as the first breaking off of the circuit takes place in the water within the automatic device. It is obvious that the closing and cutting off of the electric circuit takes place only under the control of the flowing 105 water and that should there not be any water, the electric circuit will not be closed even when one of the taps or cocks is opened.

The apparatus according to our present invention has the great advantage of not 110

requiring any electric switch and that it may be connected to any suitable number of taps or cocks.

It is obvious that many constructional changes may be introduced without departing from the scope of our present invention which has been clearly set forth in the appended claims.

We claim as our invention:

- 10 1. An automatic device for controlling the electric circuit of an electric heater, comprising a body portion adapted to have water circulated therethrough; a piston in said body portion having a contact member thereon; a rod secured to said piston; a cross piece secured to said rod and having a pair of contacts secured thereto; a pair of contacts mounted on the body portion adapted to cooperate with said contacts on the cross piece; and a contact mounted in the bottom of the body portion cooperating with said contact member on the piston and electrically connected with one of the contacts on the body portion, the contacts on the piston and in the bottom of the body portion breaking contact before the contact of the pairs of contacts are broken when the water ceases to flow through the body portion.

- 30 2. An automatic device for controlling the electric circuit of an electric heater comprising a body portion adapted to have water circulated therethrough; a piston in said body portion having a contact member thereon; a rod secured to said piston; a spring for said rod; a cross piece secured to said rod and having a pair of contacts secured thereto; a pair of contacts mounted on the body portion adapted to cooperate with said contacts on the cross piece; and a contact mounted in the bottom of the body portion cooperating with said contact member on the piston and electrically connected with one of the contacts on the body portion, the contacts on the piston and in the bottom of the body portion breaking contact before the contact of the pairs of contacts are broken when the water ceases to flow through the body portion.

- 50 3. An automatic device for controlling the electric circuit of an electric heater comprising a body portion adapted to have water circulated therethrough; a piston in said body portion having a contact member thereon; a rod secured to said piston; a spring for said rod; a cross piece secured to said rod and having a pair of contacts secured thereto; a pair of contacts mounted on the body portion adapted to cooperate with said contacts on the cross piece; a contact mounted in the bottom of the body portion cooperating with said contact member on the piston and electrically connected with one of the contacts on the body portion, the contacts on the piston and in the bottom of the body portion breaking contact before the contact of the pairs of contacts are broken when the water

ceases to flow through the body portion; and an inlet and an outlet on the body portion for the water.

4. An automatic device for controlling the electric circuit of an electric heater, comprising a body portion adapted to have water circulated therethrough; a piston in said body portion having a contact member thereon; a crosspiece associated with said piston and having a contact secured thereto; a contact mounted on the body portion adapted to cooperate with the contact on the crosspiece; and a contact mounted in the bottom of the body portion cooperating with said contact member on the piston and electrically connected with the contact on the body portion, the contacts on the piston and in the bottom of the body portion breaking contact before the contact on the cross piece and its cooperating contact break contact when the water ceases to flow through the body portion

5. An automatic device for controlling the electric circuit of an electric heater, comprising a body portion adapted to have water circulated therethrough; a piston in said body portion having a contact member thereon; a cross piece associated with said piston and having a contact secured thereto; a contact mounted on the body portion adapted to cooperate with the contact on the cross piece; a water inlet pipe at the top of the body portion and a water outlet pipe at the bottom of the body portion, the piston being normally at the top of the body portion when the water is not flowing through the body portion; and a contact mounted in the bottom of the body portion cooperating with said contact member on the piston and electrically connected with the contact on the body portion, the contacts on the piston and in the bottom of the body portion breaking contact before the contact on the cross piece and its cooperating contact break contact when the water ceases to flow through the body portion from the inlet into the outlet.

6. An automatic device for controlling the electric circuit of an electric water heater, comprising a body portion adapted to have water circulated therethrough; a piston in said body portion having a contact member thereon; a cross piece associated with said piston and having a pair of contacts secured thereto; a pair of contacts mounted on the body portion adapted to cooperate with the contacts on the cross piece; a water inlet pipe at the top of the body portion and a water outlet pipe at the bottom of the body portion, the piston being normally at the top of the body portion when the water is not flowing through the body portion; and a contact mounted in the bottom of the body portion cooperating with said contact member on the piston and electrically connected with the contact on the body portion, the contacts on the piston and in the bottom of the body portion

tion breaking contact before the contacts on the cross piece and its cooperating contacts break contact when the water ceases to flow through the body portion from the inlet into 5 the outlet.

7. An automatic device for controlling the electric circuit of an electric water heater, comprising a body portion adapted to have water circulated therethrough by means of 10 an inlet and an outlet; a piston in said body portion and adapted to make an electrical contact with the bottom of said body portion; a rod secured to said piston; a contact on said rod adapted to cooperate with a contact on the 15 body portion; and means for normally keeping said contacts separated when no water is flowing through the body portion, said means acting to separate the contact on the piston before the contact on the piston 20 rod separates from the contact on the body portion when the water ceases to flow through the body portion.

8. An automatic device for controlling the electric circuit of an electric water heater, comprising a body portion adapted to have 25 water circulated therethrough by means of an inlet and an outlet; a piston in said body portion and adapted to make an electrical contact with the bottom of said body portion; a rod secured to said piston; a contact on said rod 30 adapted to cooperate with a contact on the body portion; and springs for normally keeping said contacts separated when no water is flowing through the body portion, said 35 springs acting to separate the contact on the piston before the contact on the piston rod separates from the contact on the body portion when the water ceases to flow through the body portion.

In testimony whereof we affix our signatures.

ANGEL A. GRASSI.
RAFAEL de OLIVEIRA CÉZAR.
